UNITED STATES PATENT OFFICE.

EUGENE F. HUG, OF ELGIN, OREGON.

ELECTRIC-LIGHT BRACKET.

No. 823,533.

Specification of Letters Patent.

Patented June 19, 1906.

Application filed June 19, 1905. Serial No. 266,065.

To all whom it may concern:

Be it known that I, EUGENE F. HUG, a citizen of the United States, residing at Elgin, in the county of Union and State of Oregon, have invented certain new and useful Improvements in Electric-Light Brackets, of which the following is a specification.

Electric lights, and more particularly those of the incandescent type generally used in dwellings and offices, are required to be moved frequently to adapt them to new positions, according as the light is to be focused at one point or another. These lights are generally suspended from the ceiling by means of electric cords, which may be lengthened or shortened or drawn to any position by attaching a string to the lamp or its suspending-cord and drawing it in the desired direction and attaching said string to the wall, window, door, or other convenient portion of the room. This practice requires time, and a string is not always convenient at hand. Hence the inconvenience and annoyance of not having the light at the desired point must be endured. This invention provides a pivotally-suspended arm upon which the lamp is mounted to travel, thereby admitting of adjusting the lamp to any position within the sweep of the arm.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of an electric-light support or bracket embodying the invention. Fig. 2 is a transverse section of the supporting-arm, showing the parts on a larger scale, the dotted lines illustrating the relative position of the trolley or carrier from which the lamp is suspended. Fig. 3 is a transverse section of the pivot-joint or swivel-support of the bracket-arm.

Corresponding and like parts are referred to in the following description and indicated in all the views of the drawings by the same reference characters.

This invention contemplates a pivotally-

supported arm 1, mounted so as to swing in an approximately horizontal plane. The electric lamp 2 is mounted to travel upon the arm 1, hence may be readily adjusted to any position within the range of movement of the arm, the radial adjustment being effected by shifting the lamp longitudinally upon the arm and the horizontal adjustment being attained by swinging the arm to the required angular position. The arm 1 may be of any length and supported in any manner to admit of its pivotal or horizontal swinging movement. In one manner of supporting the arm 1 a plate 3 is provided and is adapted to be rigidly attached to the ceiling or other convenient support, and a second plate 4 is connected to the plate 3 in a manner to readily turn, the arm 1 being carried by the plate 4 and movable therewith. In the preferable construction the supporting-plate 3 and the turn-plate 4 are of circular formation, and a rim 5, pendent from the plate 3, is inturned at its lower edge to embrace an outer flange of the turn-plate 4. The two plates 3 and 4 are joined so as to provide a swivel connection to admit of turning the arm 1 freely in any direction. A brace 6 strengthens the arm 1 and is rigidly connected to the turn-plate 4 and may be of any design to give a pleasing and ornamental effect to the fixture or bracket.

The lamp 2 may be of any type and is suspended from the arm 1 by means of an electric cord 7, which may be lengthened or shortened to admit of raising or lowering the lamp. A take-up device 8 is provided in the length of the suspending-cord 7 and may be of any construction, it being preferred to employ an automatic contrivance comprising a spring-actuated drum and coöperating ratchet-pawls, whereby the lamp may be raised or lowered in substantially the same manner as a spring shade-roller. A carrier or trolley 9 is mounted to travel upon the arm 1, and the lamp 2 is attached to and suspended therefrom.

The electric current may be supplied to the lamp in any manner; but it is preferred to utilize the arm 1 as a conductor, and for this purpose said arm is longitudinally split or divided, the sections being electrically insulated from each other to serve as leads for the outflowing and the return current. The inner ends of the sections of the arm 1 are electrically connected with pole-pieces 10 and 11 of a rosette centrally disposed with reference

- to the swivel connection of the arm or bracket, the connection between said pole-pieces and the sections of the arm being such as not to interfere with the free rotation or 5 pivotal movement of the arm. The supporting-wheels of the trolley or carrier 9 make electric connection with the respective sections of the arm 1, and the wires of the electric cord 7 are connected with the respective supporting-wheels. It is to be understood that the supporting-wheels of the trolley or carrier are electrically insulated from each other, so as to preclude the possibility of short-circuiting the lamp.
- 15 Within the purview of the invention it is contemplated to support the bracket or fixture in any manner so as to swing in a circle or in the arc of a circle, according to existing conditions and the particular design of the 20 fixture. In the preferable structure it is contemplated to have the arm 1 swing in a complete circle, so as to cover a wide range of space. In any angular position of the arm 1 and in any position of the lamp with reference to said arm the electric current is 25 maintained. Hence the lamp may be instantly shifted to any required position and raised or lowered without necessitating interruption of the circuit or the tightening or loosening 30 of any fastening or part.
- Having thus described the invention, what is claimed as new is—
1. An electric-light support or fixture comprising an arm pivotally supported to swing 35 in an approximately horizontal plane and constituting a conductor, and an electric

lamp mounted to travel upon said arm and deriving current therefrom by direct contact in any adjusted position.

2. An electric-light fixture comprising a 40 pivotally-mounted arm composed of longitudinally-arranged bars electrically insulated from each other and forming conductors, an electric lamp mounted to travel upon the members of said arm and receiving current 45 therefrom in any adjusted position, and means for adjustably connecting the lamp with the said arm.

3. An electric-light fixture comprising a swinging arm embodying longitudinal sections electrically insulated from each other, means for supplying an electric current to 50 said sections, and an electric lamp mounted to travel upon the arm and in electric connection with the respective sections thereof.

4. An electric-light fixture comprising a pivotally-mounted arm comprising longitudinal sections electrically insulated from each other, a carrier mounted to travel upon 55 said arm and having electrically-insulated parts in electrical connection with corresponding sections of the arm, an electric lamp, an electric cord connecting said lamp with the respective parts of the carrier, and a take-up in the length of said electric cord to 60 admit of lengthening and shortening it.

In testimony whereof I affix my signature in presence of two witnesses.
